PARACHUTE ACTUATOR TEST CHAMBER

James Robert King, Van Nuys, and Gerald D. Myers, Sepulveda, Calif., assignors to King Nutronics Corporation, Van Nuys, Calif.

Filed Dec. 28, 1970, Ser. No. 26,678

Term of patent 14 years

Int. Cl. D10—05

U.S. Cl. D52—1

FIG. 1 is a top front, left side perspective view of a parachute actuator test chamber showing our new design;

FIG. 2 is a top rear, right side perspective view thereof;

FIG. 3 is a front end elevational view thereof;

FIG. 4 is a bottom plan view thereof.

We claim:

The ornamental design for a parachute actuator test chamber, substantially as shown.
